J. E. DIAMOND

PISTON

Original Filed May 18, 1922

James Edward Deamond *INVENTOR*

UNITED STATES PATENT OFFICE.

JAMES EDWARDS DIAMOND, OF MOUNT VERNON, NEW YORK, ASSIGNOR TO THE CLEVELAND TRUST COMPANY, OF CLEVELAND, OHIO, A CORPORATION OF OHIO.

PISTON.

Application filed May 18, 1922, Serial No. 561,997. Renewed September 14, 1927.

This invention relates to engines, steam, internal combustion, Diesel, etc., and has for an object the provision of a piston which may be fitted with minimum clearance in an engine cylinder, insuring against piston slap or clatter, and the prevention of the commonly known and undesirable oil pumping in internal combustion engines, at all temperatures and speeds of the engine.

With this as one of the objects in view, the invention consists of a piston having a skirt which is yielding, circumferentially, radially, or yielding both circumferentially and radially in combination and simultaneously, and is adapted to have a snug sliding fit in the cylinder so that upon the expansion of the piston either locally or generally due to the temperature conditions within the engine, the provisions made will eliminate the possibility of the piston seizing or scoring in the cylinder, even with the cylinder in a comparatively cold state, and after the cylinder has acquired its normal operating temperature with consequent expansion, the piston will tend to occupy the same general relation with the cylinder existing originally.

The invention also consists of the constructions which will be hereafter described in detail and particularly pointed out in the appended claims. This is another detail construction of the general principles shown in the earlier Franquist Patent, No. 1,153,902. The specific construction of the present invention lends itself to much better manufacture in metal molds particularly with reference to the metal cores, which as is well known, must be subdivided into a number of parts so as to be collapsible for ready removal from the interior of a structure of the shape of a piston, that is, ones with internally projecting bosses, ribs, etc.

In the accompanying drawing Fig. 1 shows a view in perspective of a piston constructed in accordance with the principles of my invention. Fig. 2 a front elevation half in section, and Fig. 3 an end elevation half in section, Fig. 4 an end view looking into the piston and Fig. 5 a detail showing a specific construction.

Referring to the drawings, the pistons shown may be regarded as consisting of two parts, a head 1 and a skirt 2, the head being considered that part carrying the piston rings and as far down as the actual sliding or gliding surface. For reasons well known to en-

gine builders, it is necessary to depend upon the skirt of the piston to prevent the slap of the piston within the cylinder, and heretofore it has been necessary to allow considerable free play between the piston skirt and the cylinder to take care of the expansion of the piston before the cylinder walls become heated and to insure against any of the troubles previously mentioned. After the engine has been running for a comparatively long period the cylinder walls expand, since the water in the jacket becomes heated and the same necessity for compensating for expansion does not arise. However, with a piston skirt fitting as loosely as has been customary within the cylinder, the piston will slap and may also, due to this required freedom, permit the passage of the oil past the piston into the combustion chamber while the engine remains comparatively cool, that is, while the engine is picking up and sometimes also after the cylinder has expanded due to its becoming warmed up.

In order to insure quiet operation it is proposed to use a piston having a skirt that shall be partially or entirely relieved from the undesirable mechanical expansion—when this exists—produced by the thermal expansion of the highly heated piston head due to the high temperature of combustion and that shall be automatically yielding in a circumferential direction, radially, or both circumferentially and radially, as need be, to meet the conditions existing in an engine. One embodiment of such a construction is shown in the drawings and will now be described.

Projecting inwardly from the inner surface of the skirt are ribs or webs. These ribs may extend the entire inside length of the piston, may terminate directly back of the circumferential grooves or slots (3) or may be any length dictated either by the general design of the piston, such as the location of the wrist pin or by shop production considerations. In the cases where a web construction is not used, it is necessary to cast in or machine the slot or slots or groove or grooves, which while joining the circumferential slot may or may not extend to the bottom of the skirt, it being permissible in some cases to have the bottom of the skirt an unbroken circle. When the slots or grooves (4) are cast in the piston or in the boss carrying sections, the walls of the grooves preferably diverge outwardly, as is clearly shown in Fig. 5.

Circumferential slots or grooves (3-3) are cut into the outer surface of the piston separating the skirt portion of the piston either partially or entirely from the head in so far as the periphery of the skirt is concerned, terminating at or joining and passing the longitudinal slots (4) as the case may be. The sections carrying the piston pin bosses whether or not separated on the skirt periphery remain integrally connected with the piston head (1) and are, in the constructions shown, relieved from the bottom ring groove to a point below the wrist pin, although this relief (6) may extend to the bottom of the piston. This relief which may be produced in the manufacture of the piston casting or may be machined in, is usually essential, but its exact proportions such as depth and extent must be determined for each case. Its circumferential extent is dependent upon a number of variants, but it is my usual practice to carry this relief from the zone of the piston pin bosses well beyond the longitudinal slots (4) starting with a maximum depth of relief directly coincident with an element passing thru the wrist pin axis and gradually decreasing to nothing at a point beyond the longitudinal slots (4). Among the reasons for this relief is that it provides space to accommodate the mechanical expansion of the boss-carrying portions of the skirt produced by the thermal expansion of the head and a flexure of this portion of the piston due to the deflection of the wrist pin under load. I locate the maximum depth of relief on the boss carrying sections, as just described, partly because I believe that the greatest amount of actual outward movement of these sections is along a longitudinal line passing thru the wrist pin axis. Progressively decreasing clearance is provided from this line of maximum clearance beyond the slots (4) and toward the center of bearing sections 7 of the skirt, the outside diameter across which is the maximum diameter of the piston skirt. Naturally the circumferential length of the reliefs and the depth thereof vary with different pistons and must always be sufficient to permit the piston to function under operating conditions in an engine without undue friction, scoring or seizing.

In machining a piston of this character, the skirt is given a relatively snug sliding fit within the cylinder, so that even when starting up with the engine and piston cold there will be no piston slap, and due to the minimum clearance used oil pumping is largely if not entirely eliminated. Due to the high temperature of the explosive gases the piston as a whole will commence to expand with the first explosions, the head of the piston, however, becoming very much hotter, will expand in much greater measure and amount than the skirt which is maintained considerably cooler than the head by reason of dissipation of much of the heat of the head before it reaches the skirt. In the construction in which the piston head and skirt are peripherally integral, the thermal expansion of the head is usually sufficiently great to expand or move outwardly mechanically the boss carrying portions of the skirt. These boss carrying portions tend, due to their position and the forces created by the expansion of the head, in my construction of the ribs or webs (5), automatically to draw the floating sections either circumferentially around the walls of the cylinder or to flatten the arc of these sections, thus tending to withdraw these partially independent sections of the skirt from contact with the cylinder wall, moving the elements in the diametral plane normal to the wrist pin axis in a radially inward direction, in effect flattening these circular portions of the skirt and making such transverse diameter become the axis of some form of ellipse. The construction also provides for the actual expansion in a circumferential and radial direction or both of the floating sections that may take place due to their becoming heated. The flattening of the floating sections also serves to counteract any tendency these may have to expand radially, due to thermal conditions, and offers an automatic compensating feature.

The ribs 8, as shown in Fig. 3, are each integral with a boss 9, boss carrying wall 6, the ring flange 10 and end wall 11. In addition to all these marked advantages any tendency toward radially outward expansion due to operation conditions, of the portions of the skirt in contact with the cylinder wall (neglecting the oil film), namely, all but the relieved portions of the surface of the partially independent sections of the piston when cold, and preferably the entire surface of said sections when under normal operating conditions is provided for in the constructions suggested, the ribs or webs 10 being rigid enough to carry the load due to the impulse force and rod angularity at the same time having sufficient "give" automatically to compensate for the excess expansion, this being taken up by the grooves in webs 5.

The construction is compensating with respect to normal and excess expansion in at least the several ways shown. The expansion of the piston skirt will therefore be held within proper bounds and the piston will operate within the cylinder without seizure or scoring, yet at the same time maintaining a snug sliding fit, which will prevent piston slap, and will, due to such snug sliding fit, tend to keep the oil from working past the piston skirt and beyond the head. After the engine has been running a comparatively long period of time the water in the jacket becomes heated and the cylinder expands,

but any free play which would otherwise occur will be automatically compensated for by a tendency of the skirt portions of the piston to resume, relatively, their normal 5 positions.

Another advantage of a skirt of this character is that ample provision is made to take care of distortion of the cylinder from a true circle in cross section, such cylinder distortion being more or less common with internal 10 combustion engines, and with a skirt that is substantially, radially and circumferentially compressible throughout, a considerable portion of, or for the entire skirt length any distortion of the cylinder will cause one or 15 more sections of the piston to yield and obviate the likelihood of seizure.

While I have shown a particular embodiment of the earlier Franquist invention in 20 constructing a piston which is adapted to yield circumferentially, radially or both simultaneously due to mechanical expansion conditions set up within the piston by the heat encountered in operation as well as being yielding due to contracting with the cylinder wall when expanding and lending it 25 very well to casting in dies, etc., yet it is the intention to cover broadly a piston having a skirt which has been freed entirely or 30 in part from the mechanical expansion produced by the thermal expansion of the piston head, and which skirt is circumferentially, radially or simultaneously circumferentially and radially yielding to the flexure exerted by

the cylinder walls when the skirt portion is 35 expanded, and that due to the utilization of the mechanical expansion of the portions of the skirt integral with the head, an automatic compensatory element in the expansion and contraction of the piston skirt due to thermal 40 conditions is introduced.

What I claim as new and desire to secure by Letters Patent is:

1. A piston for an internal combustion engine, having a head, a skirt and piston pin 45 bosses on the skirt, said skirt having slots therein extending into the piston pin bosses and forming grooves therein.

2. A piston for an internal combustion engine, having a head, a skirt and piston pin 50 bosses on the skirt, said head and skirt being partially separated by a circumferential slot and said skirt being further provided with vertical slots leading from the circumferential slot and extending into the piston pin 55 bosses and forming a groove therein.

3. A piston for an internal combustion engine comprising a head and a skirt, the skirt having oppositely disposed, exteriorly relieved, boss carrying sections connected to 60 the head and provided with longitudinal slots having outwardly diverging walls, and oppositely disposed bearing sections separated from the head by circumferential slots and united to the boss carrying sections. 65

In testimony whereof I hereunto affix my signature this 21st day of February, 1925.

JAMES E. DIAMOND.
